UNITED STATES PATENT OFFICE.

LEEO CLARK, OF LA SALLE, ILLINOIS, ASSIGNOR OF ONE-HALF TO HARRISON FRANKLIN, OF LA SALLE, ILLINOIS.

WOOD-SAWING MACHINE.

Application filed August 24, 1921. Serial No. 494,999.

To all whom it may concern:

Be it known that I, LEO CLARK, a citizen of the United States, residing at La Salle, in the county of La Salle and State of Illinois, have invented new and useful Improvements in Wood-Sawing Machines, of which the following is a specification.

My present invention pertains to wood sawing machines, and it contemplates the provision of a device that is simple in construction and one that may be easily operated by one person and this without liability of accident.

The invention also contemplates the provision of a wood sawing machine whereby a large amount of wood may be quickly and expeditiously sawed and when occasion demands the blade of the device is capable of being raised or lowered to permit pushing 20 of the log on the support thereby enabling the cutting of long or short lengths.

The invention in all of its details will be fully understood from the following description and claim when the same are read 25 in connection with the drawings, accompanying and forming part of this specification, in which:

Figure 1 is a top plan view of the sawing machine and showing the receiving rollers 30 and table of the machine.

Figure 2 is a longitudinal side elevation of the device.

Figure 3 is a sectional view similar to Figure 2 and showing the balance wheel in 35 its raised and lowered positions.

Figure 4 is a sectional view of the frames that support the receiving rollers of the device.

Figure 5 is a detailed view showing the 40 boxes of the main pulley shaft extending into the box of the main frame.

Similar numerals of reference designate corresponding parts of all of the views of the drawings.

45 My novel device comprises the frame 1 that rests on supports and is secured thereto in any approved manner and secured on the frame 1 by means of the straps 2 is a revoluble shaft 3 having a pulley 22 at the 50 inner end thereof that derives rotary motion from a source of supply by means of the belt 23.

Adapted to be swung upwardly and downwardly on the shaft 3 and supported on the

frame 1 is a swinging frame 4 of angular 55 form in cross section. The frame 4 is provided with equi-distant straps 5 that receive revoluble shafts 7 and 19 that are arranged in the collars 6 and 20 as illustrated in Figure 1.

The shaft 20 is provided at one end with a balance wheel 21 and at its inner end with a beveled gear or pinion 18 that meshes with the pinion 17 of the shaft 3, and the shaft 7 is also provided at one end with the 65 pinion 8' that meshes with the gear 17 of the shaft 3.

At the inner end the frame 4 is provided with a shaft 10 having a pinion 9 that meshes with an outer pinion 8 of the shaft 7 70 and the shaft 10 is provided outside the frame 4 with the cutting saw 11 that is splined or otherwise secured on the shaft 10.

By reference to the drawings it will be seen that a frame 15 is arranged on supports 16 and this frame 15 is also secured 75 on the support that receives the frame 1.

This frame 15 is provided with rollers 14 to receive the log 12 and at its inner end the frame 15 is provided with the 80 table 13 that supports the log 12 in proper position during the cutting operation.

In the practical operation of the device the logs are fed on the rollers 14 until they arrive at the proper position on the table 13. 85 The angular frame 4 is then moved from the position shown in Figure 2 to the position shown in dotted lines in Figure 3 by exerting pressure on the foot-lever 24 that is provided with the rod 25 which in turn is secured to the angular frame 4. This downward movement of the foot-lever 24 will, in conjunction with the weight of the saw 11, easily move the frame to the cutting 90 position. Power is applied to the shaft 3 95 through belt 23 and pulley 22. Rotary motion of the shaft 3 will be attended by rotary motion of the shafts 19 and 7 which manifestly will impart rotary motion to the shaft 10 and in turn operate the blade 11. 100 When a log or piece of lumber has been cut the blade may be lifted upwardly by downward pressure on the counter-balance wheel 21 and hence the log or succeeding log may be readily positioned to receive the next operation of the blade.

It will be noted from the drawing and particularly Figure 1 thereof, that the frame

15 is broken away at the point where the blade 11 moves downwardly to bear against a log.

My invention is so constructed that even 5 cutting of logs or other large blocks of wood is assured at all times and this with but a minimum amount of effort on the part of those operating the device and because of the construction of 10 the pinions and shafts and their relative arrangement with respect to the frame 4 adjustment of the blade may be made without the necessity of cutting off the source of supply and energy derived therefrom. 15 This will be appreciated as quite an item when it is considered that if for any reason it becomes necessary to discontinue the cutting of a log the operation may be suspended by simply pulling down on the 20 counter-balance wheel and hence the liability of accident to the operator or the device is effectually precluded.

I would distinctly have it understood that I do not wish to confine myself to the exact 25 construction or relative arrangement of parts as specified and illustrated, and this for the reason that such changes or modifications may be made as fairly fall within the scope of the claim appended.

30 The main shaft as shown in Figure 5 has the boxes turned at their ends to extend into

the box of the frame 2. Thus the boxes 4* will preclude the frame carrying the saw from resting entirely on the shaft 3.

Having described my invention, what I 35 claim and desire to secure by Letters Patent is:—

In a wood sawing device the combination of supports, a frame mounted on the supports and a shaft upon which the frame is 40 rocked, a pinion splined on the shaft, a shaft transverse to the first named shaft having a pinion that meshes with the pinion on the first named shaft, a balance-wheel mounted on the opposite end of the second 45 named shaft, a shaft extending in the same plane as the second named shaft, pinions mounted on the ends of the last-named shaft; one of which pinions meshes with the pinion on the first shaft and a shaft extending parallel with the first shaft and having a pinion that meshes with one of the pinions of the third named shaft, a cutting blade secured on the last named shaft and a log receiving frame and table.

55 In testimony whereof I have hereunto set my hand in presence of two subscribing witnesses.

LEEO CLARK.
